PAGE 2

Fig. 3.

Fig. 4.

Fig. 5.

FIG. 1 is a top plan view of a power unit for a saw mill carriage or the like, showing my new design;

FIG. 2 is a left side elevational view of my new design;

FIG. 3 is a front elevational view of such design;

FIG. 4 is a rear elevational view thereof; and

FIG. 5 is a right side elevational view of the same.

I claim:

The ornamental design for a power unit for a saw mill carriage or the like, as shown.
